George A. Hart

John Pickering, Simeon Goodrich, & George Hart. Patented, 1861.
Sellers Patent.

Dated June 22d, 1861.

(This Schedule is made to the Sellers Patent, and making part of the same, containing a description in the words of the said John Pickering, Simeon Goodrich and George A. Hart, inventors, of their improvements in the machine for cutting fence pickets.

(To all whom it may concern, Be it known that we John Pickering and George A. Hart of St. Louis and Simeon Goodrich of Boston in the State of Massachusetts and Simeon Goodrich of Boston in the State of New York have invented a new and useful improvement in a machine for cutting fence pickets and that the following is a full and exact description thereof. The machine for making the pickets is in the form of a cylinder,

about five feet in diameter of wood or metal, the rim of which is to be a wide shallow cylinder of the picket head is mounted, this rim of which is to be under this same shape, so that picket heads mounted through this cylinder will be thrown up opposite each other to form pickets in diameter as long as the picket head is mounted, this leaves room for the passage of the chips as they are cut, this cylinder is to be hollow with a broad core only on one side the other entirely open. A shaft is put through by a hub fastened to this outer head on which it revolves. The edge of this hub is so cut down enough for the chips to pass off. This hub is fastened to the cylinder with the thickness of the hub, so as to leave with the face of the cylinder, the edge to form a perfect mirror with the sides to enable it to pass down and cut smooth, in the under hand of this cylinder are two plain iron plates with iron corner brackets and so set as to convenient cutting first, which will have the same effect as shaving a smoothing plane across a board with a common before the other instead of shaving it straight forward, the cutting end is about 15° in the revolving position the stuff is planing with not convenient contact with the iron which is coming upon the opposite side, then can be a slab gunpowder carried to the other stuff over against it. This hub or cylinder is set on a frame of suitable height and size kept revolved by a crank or strap and the picket head end of the picket is to be placed against a gunpowder suitable distance to bring the other end into a proper situation to be cut, which is to be more dangerous than as the iron end is coming over.

(What we claim is our own invention and not previously known in the now described machine is the cylinder in the form of the edge of a chip cutting tools. The same edge may be made up of one or more — galvanized plates, and down is to be made by a crank.

hops - boil and strain off eight, gallons, - then add 25 lbs white sugar - scalded; strain it, then add 1 lb cloves when hot and put it in a keg. - then cool add two gallons improved rheumatic drops. Dose for an adult from $\frac{1}{2}$ to 1 wine glass full and repeat at discretion till cured. - Improved Rheumatic Drops. Take of yarrow myrt 1 lb; of Golden Seal full of Mayhaw shrub; Capsicum toy, the whole to be put in one gallon of Cherry brandy, wine or high proof brandy and let it be well shaken together. Dose from one to two spoonfuls.

That we claim as our discoveries and which we desire to secure by Letters Patent, are the before described modes of preparing and administering the above medicines for the purposes herein named.

Witnesses.

John Fichener, Siah Goodrich, & Geo. C. Hart - State of N.Y.
Sellers Patent

(Dated June 22d, 1836.

(The Schedule referred to in these Sellers Patent, and making part of the same, containing a description in the words of the said John Fichener, Siah Goodrich, and George C. Hart themselves, of their Improvement in the Machine for cutting fence Pickets.

To all to whom these presents shall come, Be it known that we John Fichener and George C. Hart of Ithaca, and Siah Goodrich of Brooten in the County of Tompkins and State of New York have invented a new & useful Improvement in making fence pickets, and that the following is a full and exact description thereof. The machine for making the pickets is in the form of a cylinder

about two feet in diameter of wood or metal, the rim of which is to be as wide as the length of the Picket head is wanted, the surface of which is to be made the same shape as the pickets are wanted; through this cylinder are cut two throats opposite each other one & $\frac{1}{2}$ inches wide and as long as the picket heads are wanted; the throats are for the passage of the chips as they are cut, this cylinder is to be hollow with a head or cover, only on one end & the other entirely open. A shaft is put through by a hub fastened to this end or head on which it revolves. The edge of the iron or chisel is set low enough for the chips to pass off. The chisel is set into the cylinder the thickness of the chisel, so as to be even with the face of the cylinder, the edges to form a perfect mitre with all sides to enable it to pare down and cut smooth; in the end or head of the cylinder are two planes transverse with one corner bevelled and so set as to commence cutting first, which will have the same effect as shaving a smoothing plane across a board with one corner before the other instead of shaving straight forward; the head or end is about $\frac{1}{2}$ an inch bevelled so that the stuff in planing will not come in contact with the iron which is coming up on the opposite side, there can be a slab gauge or carriage to shave the stuff over against. This wheel or cylinder is set on a frame of suitable height and size & revolves by a crank or shaft to cut the picket heads. One end of the picket is to be placed against a gauge at a suitable distance to bring the other end in a proper situation to be cut, which is to be moved up as fast as the iron cut is coming over.

What we claim as our own invention and not previously known in the above described machine is the cylinder & the form of the edges of chisel or cutting tools. The same chisels may be operated upon a small galvanizing up & down on slides by a crank.
